UNITED STATES PATENT OFFICE.

CARL M. DREHER, OF NORA SPRINGS, IOWA.

STORE COUNTER.

Application filed April 3, 1923. Serial No. 629,712.

To all whom it may concern:

Be it known that I, CARL M. DREHER, a citizen of the United States, residing at Nora Springs, in the county of Floyd and 5 State of Iowa, have invented certain new and useful Improvements in Store Counters, of which the following is a specification.

My said invention relates to a counter for stores and it is an object of the same to provide a device of this character which shall 10 serve as a means for displaying merchandise in bulk, the counter being so arranged as to facilitate the packaging of the merchandise and serving also for storage of the 15 packages of retail size.

A further object of the invention is to provide a construction of the character indicated which shall be of the knockdown or collapsible type whereby it may be packed 20 in small compass for shipping.

Still another object is to provide a device of the character indicated which shall be dust-proof to a high degree thereby obviating one of the objections to numerous varieties of counters now in use.

Another object is to provide supporting means for the transparent front and side members of the various compartments which means shall permit quick replacement of 30 broken or defective parts.

Referring to the accompanying drawings which are made a part hereof and on which similar reference characters indicate similar parts,

Figure 1 is a perspective of my improved device viewed from the front,

Figure 2 a rear perspective of the same,

Figure 3 a vertical section,

Figure 4 a fragment showing the connection between certain longitudinal and transverse members,

Figure 5 a section through a joint shown in Figure 4,

Figure 6 a detail of a glass panel; and

Figure 7 a detail of a rear door.

Fig. 8 is a perspective view of the device knocked down.

In the drawings reference character 10 indicates the bottom of the device which is 50 preferably covered with galvanized sheet iron or other analogous material 11 to prevent waste, to keep out moisture and vermin and for other purposes. The bottom is supported at a distance from the floor by front

and rear members 12 and 13 and end members 14 and 15. Posts 16 are attached to the front member 12 by screws, said posts extending upwardly and supporting a corner-piece comprising two beams 17 and 17' separated at intervals by tenons 18 on the posts 16 to maintain open slits between the beams. The posts are cut away at the lower end so that they rest on the part 12 but have a depending projection 19 extending down to the floor of the counter and secured to part 60 12 by screws. The tenons 18 at the top of the posts extend to the top of the beam 17, the beam 17' being supported on the shoulder adjacent to the tenon. It will be observed that the front side of each post is 70 flush with the front face of the member 12 while the beam 17 overhangs the same and that the slits between the beams 17 and 17' provide ready access to the grooves at adjacent sides of successive posts and at the 75 upper edge of part 12, the purpose of said grooves being to receive a sheet 20 of glass or other transparent material edged with paraffined tape 20'.

About midway of the counter is a longitudinal vertical partition 21 extending from end to end of the counter and connected at its ends to side pieces 22 and 23 mortised to the end pieces 14 and 15. At its upper end this partition is cut away at intervals to 80 provide spaces for receiving cross-beams 24 extending from front to rear of the counter and resting at the front end on shoulders of the posts 16 which extend inwardly from corner beam 17' to the same extent that the beam 17 overhangs them. Screws 25 extend through members 16, 17, 17' and 18 to hold the parts together. For holding the joists 24 in place I have provided a series of metallic clips 26 each of which is forked at 85 its rear end to match a slit in one of the crossbeams and has a hole to receive a screw 27 extending into the corner piece 17'. At its forward end the clip is bent to form a hook 28 engaging between corner piece 17 and a post 16 and brads 29 are driven through the bifurcated parts of the clip into the joint 24.

The partition 21 is supported at its rear end by lower transverse partitions 30. 105 These partitions are supplied with grooves indicated by dotted lines at 31, 31' and the longitudinal partition is also provided with

grooves indicated at 32 matching with the grooves 33 in the posts 16 and with slits 34 (Figure 1) cut in the joist 24. Sheets 34' of glass or other transparent material are inserted through the slits and are held in place by them and by the vertical and horizontal grooves to form transparent upward continuations of the partitions 30, thus providing compartments extending from the 10 top to the bottom of the counter and from front to rear of the counter at the bottom, which partitions are transparent at the front and sides, thus providing for clearly displaying the bulk merchandise placed in such 15 compartments, such as powdered, granulated or whole grain products.

At the rear of the longitudinal partition 21 is a horizontal shelf 35 forming an upper closure for the compartments between the 20 partitions 30 and serving to brace the vertical partition 21.

At the rear of the counter are equally spaced posts 36 cut away to form shoulders resting on the rear member 13 and extending 25 at 37 down to the floor as shown in Figure 3. These posts are connected by screws 38 respectively to the rear member 13 and to a rear corner beam 39 which differs from the corresponding front corner structure 30 in that it is formed in a single piece having openings to receive the upper extensions 40 on posts 36. The posts are set so that the corner beam 39 will overhang them and shoulders are thus formed on which the 35 crossbeams 24 rest at their rear ends. Grooves are provided at 41 in adjacent faces of successive posts and leaves 42 of resilient sheet metal are mounted in said grooves. These leaves form vertically 40 slideable rear closures for the compartments containing bulk merchandise and the horizontal shelf 35 is undercut as shown in Figure 3 to provide a space for the reception of the forwardly bent upper ends of these closures, 45 whereby access of dust and other foreign material into the compartments is prevented, the upper edge of member 13 being beveled as shown at 42' for a similar purpose.

Each closure has a handle at 43 formed 50 by bending a projecting part of the sheet metal downward and backward. It will be evident that by pulling back on the handle the upper part of the leaf may be bent so as to pass by the lip on shelf 35 and therefore 55 after the closure 42 may be raised so as to be out of the way while the merchandise is removed from the bulk compartment at the rear side. This provides a convenient arrangement for the packaging of merchandise which may be put up, for example in packages as desired by customers, said packages being then set on top of the counter for tying etc. and when finished stored in the space above the shelf 35 from which 60 they can be readily handed out to customers.

By the use of this counter the packaged goods are out of sight and out of the way. Such an arrangement is not only slightly and convenient but a very sanitary storage is thus provided for merchandise since the compartments will hold a large amount of merchandise in bulk in a location where it will be kept clean and free from the attacks of rodents, insects, etc. The storage space for small packages also can readily be kept 70 clean and there is little danger of breakage of such packages while stored on the shelf 75 35. The entire space above the shelf is preferably left as a single compartment, but partitions can readily be inserted if desired 80 and such change is considered to be within the scope of my invention.

An upper closure is provided for the entire counter comprising a fixed section 44 and a pair of movable doors 45 and 46 which 85 may be hinged to the fixed section as indicated at 98 (Fig. 3). The line of division between the fixed and movable parts is so located that the joint falls at the rear of the partition 21 so that any dust which may 90 enter the space behind the doors will not have access to the bulk storage compartments but will fall into the space above the shelf 35 where it can be readily removed and will not get into the merchandise itself. 95 Should it be desired to still further protect the merchandise in bulk against the access of dust it will be a simple matter to provide a strip of packing on the underside of the doors 45 and 46. The crossbeams 24 at the 100 ends of the counter are stepped out to overhang the side pieces 22 and 23 to form a finish for the counter and corner braces 47 are secured to these crossbeams and to the respective corner pieces 17 and 39 for further reinforcement.

It is desired to call special attention to the knockdown or collapsible arrangement of the device. By removing the various screws holding the parts together the posts 16 and 36 may be taken down, the corner beams and cross-beams separated, the doors 42 stacked up separately and all the smaller parts may be located in the compartment formed by parts 12, 13, 14 and 15 and the bottom carried thereby. The glass being merely loosely supported in the slots is first slipped out and may be packed with the other parts or shipped separately as is found preferable. This provision for easy removability of the 110 glass is also important in replacing broken or defective glass since it requires a minimum of time and care or experience to merely slide a sheet of glass out of its 115 grooves and replace it with another. After 120 the smaller parts have been packed in the bottom the top pieces 44, 45, and 46 may be placed in position over the same and fastened down in any convenient manner to 125 form a cover for the chest or box thus pro- 130

vided when the whole may be shipped safely and at a minimum freight charge. When the parts arrive at their destination it is a simple matter to set up the counter and requires no tools save a screw-driver.

It will be obvious to those skilled in the art that many modifications of my device may be made without departing from the spirit of the invention, therefore I do not limit myself to the precise form shown in the drawings and described in the specification but only as indicated in the appended claims.

Having thus fully described my said invention, what I claim as new and desire to secure by Letters Patent, is:

1. A store counter comprising outer walls and partitions forming a plurality of compartments for merchandise in bulk each compartment extending from top to bottom and from front to rear of the counter, a package compartment, a vertical partition extending lengthwise of the counter separating the first-named compartments from the package compartment, a lid for the bulk storage compartments, the said lid being hinged over said package compartment to exclude dirt from the bulk storage compartment, substantially as set forth.

2. In a knockdown store counter having a series of display compartments along the front of the counter for merchandise in bulk, spaced posts along the front and rear of the counter, beams running lengthwise of the counter adjacent to said posts, tenons on the posts extending upward through the beams, crossbeams extending between said beams and resting at their ends on oppositely located posts, clips secured to the crossbeams each clip having a hook engaging between the side of a tenon and the outer section of the adjacent longitudinal beam, and a swinging door in the top of the counter above the parts held together by said clips, substantially as set forth.

3. In a knockdown store counter having a series of display compartments along the front of the counter for merchandise in bulk, spaced posts along the front of the counter, beams running lengthwise of the counter supported by said posts the front beam having one or more vertical slits, means below said slits for receiving sheets of glass inserted through the slits and holding them in place, tenons on the posts extending upward through the beams, crossbeams extending between said beams and resting on oppositely located posts, clips secured to the crossbeams said clip having hooks engaging between the end of the tenon and the outer section of the front beam, and a swinging door in the top of the counter above the parts held together by said clips, substantially as set forth.

4. In a store counter, a storage compartment for merchandise in bulk, a vertically slidable door therefor, and a ledge nor-

mally overhanging and contacting with the upper end of said door to prevent access of dust, substantially as set forth.

5. In a store counter, a storage compartment for merchandise in bulk, a vertically slidable door therefor having its upper end normally inclined toward the compartment, means constraining the body of the door to move in a straight line, and a ledge normally overhanging the upper end of said door to prevent access of dust, substantially as set forth.

6. In a store counter, a storage compartment for merchandise in bulk, a vertically slidable door therefor having a resilient upper end normally inclined toward the compartment, means constraining the body of the door to move in a straight line, and a ledge normally overhanging the upper end of said door to prevent access of dust, substantially as set forth.

7. In a store counter, a storage compartment for merchandise in bulk, a vertically slidable door therefor having a resilient upper end normally inclined toward the compartment, means constraining the body of the door to move in a straight line, a ledge normally overhanging the upper end of said door to prevent access of dust, and a support to receive the lower end of the door the outer part of said support sloping away from the door to carry off dust, substantially as set forth.

8. In a display counter having a compartment extending from front to rear, a vertically slidable resilient door at the other end of the compartment forwardly inclined at the upper end, guides for the sides of the door, a ledge under which the upper edge of the door engages when in closed position, the upper corners of the door being cut away to permit the forwardly bent upper portion to move toward and from said ledge, and a handle on said upper portion, substantially as set forth.

9. In a counter, a door comprising a sheet of material having a resilient forwardly bent upper end, a recurved flange at the upper end of the door bent down flat against the same, and an integral handle extending rearwardly from said recurved part, substantially as set forth.

10. In a knockdown display cabinet, a permanent bottom part having a floor with walls at its sides and ends, demountable transverse partitions therein, front and rear series of demountable posts, demountable corner beams and crossbeams supported on said posts, demountable horizontal and vertical partitions forming a storage compartment, demountable end pieces closing said compartment at the ends, and a demountable top with pivoted doors, all of said parts being detachably connected by screws and the top being constructed and arranged to

be inverted over the bottom part to provide a closure therefor after the remaining pieces have been arranged therein for shipment, substantially as set forth.

- 5 11. In a store counter, walls and partitions forming a series of display compartments along the front of the counter for merchandise in bulk, spaced posts along the front of the counter, a longitudinal partition behind said posts, guiding means on the posts and the partition, removable transparent panels held in place by said guiding

means, a beam connecting the upper ends of the posts, and crossbeams extending rearwardly therefrom said first-named beam and 15 said crossbeams having vertical slits in line with the guiding means, substantially as set forth.

10 In witness whereof, I have hereunto set my hand and seal at Washington, District 20 of Columbia, this third day of April, A. D. nineteen hundred and twenty-three.

CARL M. DREHER. [L. s.]
